United States Patent Office

Des. 177,806
Patented May 29, 1956

177,806

CAN PUNCH

Richard P. Hanner, near Charlotte, N. C.

Application July 7, 1955, Serial No. 36,863

Term of patent 14 years

(Cl. D44—29)

FIG-2

FIG-1

Fig. 1 is a perspective view of a can punch showing my new design;

Fig. 2 is a side elevational view thereof; and

Fig. 3 is a side elevational view of the side opposite to that of Fig. 2.

I claim:

The ornamental design for a can punch, as shown.
